UNITED STATES PATENT OFFICE.

ARTHUR MATTHEY, OF VEVEY, SWITZERLAND.

DRESSMAKER'S ADJUSTABLE DUMMY-SUPPORT.

1,238,423.

Specification of Letters Patent. Patented Aug. 28, 1917.

Application filed April 28, 1916. Serial No. 94,129.

To all whom it may concern:

Be it known that I, ARTHUR MATTHEY, engineer, a citizen of Switzerland, residing at Vevey, Canton of Vaud, in the Confederation of Switzerland, have invented certain new and useful Improvements in Dress-makers' Adjustable Dummy-Supports, of which the following is a specification.

The object of the present invention is the provision of an adjustable dummy-support for tailors' and dress-makers' shops and for the purpose of exhibiting clothing in show-windows.

Dress-makers' dummy-supports heretofore in use were not adapted to keep the dummies in an exact vertical position owing partly to an inexact adjustment of the supporting rod held within the pedestal and owing partly to the manner of maintaining the dummy on the said rod at different heights.

According to the present invention however the dummy support consists of a supporting rod extending through the dummy and held within a pedestal shaped so as to avoid the unevenness of the ground and provided with at least one bushing for securing the vertical position of the rod and of a device for adjusting a dummy supporting plate at different heights and at a right angle to the axis of the rod.

In the accompanying drawing several working examples of the invention are shown.

Figure 1 is a general side elevation of a dummy-support partly in section.

Fig. 2 shows on an enlarged scale an adjusting device for the plate.

Figs. 3 and 4 are sections showing two different ways of fixing the supporting rod within the pedestal.

Figs. 5, 6 and 7 are sections showing three modified forms of the base ring of the pedestal.

Figs. 8, 9 and 10 are vertical sections of other forms of adjusting devices for securing the dummy at a desired height.

Fig. 11 is a general side elevation of a support for short dummies for blouses.

Fig. 12 shows a sectional view in full size of a device for adjusting the length of the telescoping tubes from above the dummy, and

Fig. 13 is a section of a similar device for adjusting the height of the dummy on the rod from beneath the dummy.

Like characters of reference indicate corresponding parts.

According to Figs. 1 and 3 the pedestal of the dummy support is cast in metal and comprises an annular bottom piece *a* and two bushings *a*¹, *a*², placed one above the other, and which are connected to the bottom piece by three legs *a*³, *a*⁴, the whole forming a piece wherein any objectionable tension from an unequal cooling after casting are avoided, and also one which may be easily bored on a machine so as to have the axis of the bores standing vertically on the base ring. Within said bushings a rod *b* extending through the dummy is secured in a vertical position and the dummy *c* itself is sleeved on said rod by means of an upper plate *c*¹ and a lower plate *c*², the latter resting on a disk *d*¹ made in one piece with the sleeve *d* and fitting the rod *b* (Fig. 2). The sleeve *d* is provided on its outside with a conically turned-off thread *d*² and with several radial slits *d*³. It is also fitted with a hand-wheel *e* forming a nut in which the thread *e*² is cut only on a part of the bore, so as to leave the remaining part of the bore with a diameter corresponding to the inner diameter of the thread *e*⁴. This cylindrical part of the bore is then turned conically, as shown in Fig. 2, where the diameter at *e*³ is somewhat greater than at *e*⁴ so as to form a cone similar to that of the thread *d*². The nut *e* when being screwed up on sleeve *d* by means of the milled handle *e*¹ will therefore clamp said sleeve fast to rod *b* and will maintain the dummy at any desired height by means of the disk *d*¹ the upper face of which stands at a right angle to the axis of the rod *b*, and as the latter is kept in a vertical position by the pedestal the dummy must necessarily also be kept in a vertical position.

According to Figs. 3 and 4 the rod may be a pipe fixed within the pedestal either by being sleeved within the upper bushing and screwed directly into the lower bushing or by being sleeved within the upper bushing and being sleeved on a pin *b*¹ fixed to the pipe and screwed within the lower bushing.

Also the bottom piece *a* may be shaped either as is shown in Fig. 5 or as is shown in Fig. 6 with a narrow rim to avoid as much as possible the unevenness of the surface upon which it rests, or as is shown in Fig. 7, this annular bottom piece may be pro-

vided with three or more rubber feet a^5 to secure a safe and yielding contact with the supporting surface.

In order to render the dummy-support well adapted for show-windows the rod may be replaced by two telescoping tubes as shown, the relative position of one of the tubes with regard to the other being arranged so as to be moved from the top of the dummy.

In Figs. 8 to 12 are shown several forms of contrivances to accomplish this purpose.

The simplest form is shown in Fig. 8 where the hollow rod b extends only into the space between the upper plate c^1 and the lower plate c^2 and is provided at its top with a nut b^2 fixed to it. A handle g is fixed within the top plate c^1 by means of a collar g^2 and is fitted with a rod f , projecting downwardly and screwed by means of a threaded part f^1 into a nut b^2 . By turning the handle g the dummy may be fixed at any desired height determined by the position given the rod f within nut b^2 .

Figs. 9 and 10 represent two other forms of contrivances for adjusting the height of the dummy by turning the handle g . In Fig. 9 the handle is made in two parts; lower part g^0 is fixed by means of a collar g^2 to the plate c^1 of the dummy in the same manner as that shown in Fig. 8, and a movable upper part g rests on the lower part with the faced part of a disk-like nut g^1 fast to the upper part. The handle part g^0 by means of the collar g^2 is secured to a tube h which is sleeved within the tubular rod b . The end of the tube h engaged within the rod b is split into several branches h^2 and is provided with a conically shaped inner side portion tapering toward the top and fitting a conical piston f^2 fixed to the lower end of a rod f the upper end of which is threaded as indicated at f^1 and fits the nut g^1 of handle g . By turning this handle while holding fast to the part g^0 the rod f will be either screwed into nut g^1 whereby the piston f^2 by moving upward will cause the end of the tube h to be spread and to be clamped fast within pipe b , or will be unscrewed from the nut g^1 , and the piston f^2 while descending will leave the conical inside surface of the tube h thereby freeing the tube h within pipe b . The raising or lowering of the dummy c will therefore be effected by taking hold of the part g^0 and by turning the part g in the one way or the other to clamp or unclamp tube h within pipe b .

The same effect may also be obtained by the structure shown in Fig. 10 in which the handle g is fixed to the sleeve g^2 the plate c^1 and the rod f , and by fitting the lower end of rod f with a threaded part f^1 to engage the piston f^2 like a nut. In Fig. 9 are also shown feet a^5 cast on to the under-

side of the annular piece a of the pedestal as means for avoiding the effect of the unevenness of the ground or other supporting surface.

Figs. 11, 12 and 13 relate to a form of the support adapted for short dummies for blouses or for exhibiting corsets in show-windows, Fig. 11 showing a general view or the contrivances shown in detail in Figs. 12 and 13.

As illustrated Fig. 11 a metallic foot-plate a is provided with a hub a^4 wherein rod B reaching into the space between plates c^1 and c^2 of the dummy is fixed rigidly by means of a threaded part and pins set cross-wise.

A tube h , fitted at its top end with a hollow handle g made fast to the plate c^1 and provided at its bottom end with a clamping or braking device, is made to telescope with in the rod b thus forming an extension of the same. These devices are worked with one hand by holding fast the handle and by pressing with the thumb on a movable knob f^5 projecting from the top of the handle. By pressing it the rod may be lengthened or shortened at will; by letting go again the telescoping tubes will be automatically clamped fast to one another at the desired length. The plate c^2 normally rests upon the flanged part m' of a cap which is also provided with an intermediate conical part m^2 fitting over a sleeve l loosely mounted on the rod b and with which are also associated frictional devices hereinafter described in connection with Fig. 13 for normally supporting the dummy form in any desired position on the rod b .

In Fig. 12 which represents the clamped position of the device the knob f^5 is guided vertically within the top part of handle g and is linked with two similar arms f^8 to two slides f^4 fitted on a horizontal pin fast in the inside of the handle. Said slides f^4 are linked again by two arms f^8 , of equal size to a knob f^6 fixed to the top-end of a wire f which is thus held coaxially with a knob f^5 and is connected to the bottom plate f^7 of a cap f^3 containing the clamping or braking device. The inside of cap f^3 is provided with a conical portion fitting with some play to a conical piece h^1 secured to the end of tube h and is kept concentric with it by means of a set of friction-balls i seated within the walls of cap f^3 . When the knob f^5 is at rest end piece h^1 and the balls i will be kept in contact with each other by a spring k inserted between bottom-plate f^7 and the piece h^1 , and the spring k is strong enough to cause the cap f^3 to wedge the balls fast between the conical end piece h^1 and the rod b , and to brake the balls i completely so as to clamp the piece h^1 fast within rod b . If however, the knob f^5 is pressed down the spring k will be compressed and the cap f^3 130

will carry the balls *i* upward thereby releasing the contact of said balls with the conical surface of piece *h*¹. By this action the pipe *h* is free to move in either direction 5 relatively to the rod *b* and the balls *i* roll freely on the inside surface of rod *b*.

According to Fig. 13 which also shows the device in a clamped position, a cap *n* provided with a flanged part *m*¹, supports the 10 plate *c*² of the dummy, and its intermediate conical part *m*², contacts with a set of friction balls *i* seated within the conically shaped part of the wall of an inner sleeve *l*. This sleeve *l* is fitted with some play on rod 15 *b* and is pressed upward by a spring *k* inserted between a shoulder of the sleeve and a flanged part of an extension *m*³ of the cap. The pressure of this spring is sufficient to clamp the balls fast between rod *b* and cap 20 *n* and to support the weight of the dummy. If however the counteracting weight of the dummy be removed either by lifting the same up from the flanged part *m*¹ or by lifting up the extension of the cap the 25 clamping action of the spring is diminished so that sleeve *l* may be easily shifted on rod *b* in order to fix the dummy automatically at any desired height after releasing either the dummy or the extension.

30 I claim as my invention:

1. A dress-maker's dummy support comprising a base, telescoping tubular rods, the outer rod being fixed in said base, a dummy form secured to the inner rod and through 35 which dummy form the said rods pass, a conical member secured to the end of the inner rod within the outer rod, a cap member, frictional devices in the cap member adapted to engage the outer rod and said 40 conical member, means for normally maintaining the friction devices in position to clamp the outer rod and conical member together, and means for moving the cap member to release the said friction devices and 45 permit the movement of the said rods to adjust the same to position.

2. A dress-maker's dummy support comprising a base, telescoping tubular rods the outer rod being secured in said base, a 50 dummy form secured to the inner rod and through which dummy form the said tubular rods extend, a conical member secured to the end of the inner rod within the outer rod, a cap member interposed between the conical 55 member and the outer rod, a series of balls journaled within the said cap member and adapted to bear against the conical member and the inner surface of the outer rod, a spring for normally maintaining the cap 60 member in such a position that the said balls are in contact with the conical member and the outer rod to maintain the rods in a fixed position relatively to one another, and means for moving the said cap member against the 65 action of the said spring to free the fric-

tional contact of the said balls and permit the adjustment of the said rods to any one of a number of positions.

3. A dress-maker's dummy support comprising a base, telescoping tubular rods the 70 outer rod being secured in said base, a dummy form secured to the inner rod and through which dummy form the said tubular rods extend, a conical member secured to the end of the inner rod within the outer rod, 75 a cap member interposed between the conical member and the outer rod, a series of balls journaled within the said cap member, and adapted to bear against the conical member and the inner surface of the outer rod, a 80 spring for normally maintaining the cap member in such a position that the said balls are in contact with the conical member and the outer rod to maintain the rods in a fixed position relatively to one another, a handle 85 connected to the outer end of the inner rod, a movable knob mounted in the said handle, and means connecting the said knob and cap member, whereby through the movement of the knob inwardly the cap member is moved 90 against the action of the said spring to release the frictional contact of the said balls against the conical member and the outer rod to permit the adjustment of the said rods relatively to one another to any of a number 95 of positions.

4. A dressmaker's dummy support comprising a base, telescoping tubular rods the outer of which is fixed in the said base and rises therefrom, a dummy form, means for 100 supporting the dummy form from the said outer tubular rod, a handle fixed at the end of the inner tubular rod, frictional devices for securing the tubular rods in position relatively to one another, means operated 105 from said handle for releasing the frictional devices to permit the adjustment of the tubular rods to any one of a number of positions, and devices for shifting the position of the means for supporting the dummy form on 110 the outer rod.

5. A dressmaker's dummy support comprising a base, telescoping tubular rods, the outer rod being fixed in said base, a dummy form, a conical member secured to the end of 115 the inner rod within the outer rod, a cap member, frictional devices in the cap member adapted to engage the outer rod and said conical member, means for normally maintaining the friction devices in position to 120 clamp the outer rod and conical member together, means for moving the cap member to release the said friction devices and permit the movement of the said rods to adjust the same to position, and means for supporting 125 the dummy form at different heights on the outer rod.

6. A dressmaker's dummy support comprising a base, telescoping tubular rods, the outer rod being fixed in said base, a dummy 130

- form, a conical member secured to the end of the inner rod within the outer rod, a cap member, frictional devices in the cap member adapted to engage the outer rod and said 5 conical member, means for normally maintaining the friction devices in position to clamp the outer rod and conical member together, means for moving the cap member to release the said friction devices and permit 10 the movement of the said rods to adjust the same to position, a cap having a flanged portion surrounding the outer rod and adapted to support the dummy form and an intermediate conical part, a sleeve fitting loosely 15 on the outer rod and having a tapered end lying within the conical part of the cap, a set of friction balls in the conical part of the sleeve, and a spring extending between a shoulder on said sleeve and a flanged part of 20 said cap.
7. A dressmaker's dummy support comprising a base, telescoping tubular rods the outer rod being secured in said base, a dummy form through which the said tubular 25 rods extend, a conical member secured to the end of the inner rod within the outer rod, a cap member interposed between the conical member and the outer rod, a series of balls journaled within the said cap member and 30 adapted to bear against the conical member and the inner surface of the outer rod, a spring for normally maintaining the cap member in such a position that the said balls are in contact with the conical member and 35 the outer rod to maintain the rods in a fixed position relatively to one another, and means for moving the said cap member against the

action of the said spring to free the frictional contact of the said balls and permit the adjustment of any size of dummy form 40 to any one of a number of positions.

8. A dressmaker's dummy support comprising a base, telescoping tubular rods the outer rod being secured in said base, a dummy form through which the said tubular 45 rods extend, a conical member secured to the end of the inner rod within the outer rod, a cap member interposed between the conical member and the outer rod, a series of balls journaled within the said cap member, and 50 adapted to bear against the conical member and the inner surface of the outer rod, a spring for normally maintaining the cap member in such a position that the said balls are in contact with the conical member and 55 the outer rod to maintain the rods in a fixed position relatively to one another, a handle connected to the outer end of the inner rod, a movable knob mounted in the said handle, and means connecting the said knob 60 and cap member, whereby through the movement of the knob inwardly the cap member is moved against the action of the said spring to release the frictional contact of the said balls against the conical member and the 65 outer rod to permit the adjustment of the said rods relatively to one another to any of a number of positions.

In testimony whereof I have affixed my signature in presence of two witnesses.

ARTHUR MATTHEY.
